UNITED STATES PATENT OFFICE

JOSEPH H. SLOCUM, OF LOS ANGELES, CALIFORNIA

SYSTEM AND MEANS OF ELEVATING FLUID

Application filed September 20, 1923. Serial No. 663,914.

This invention relates to process and apparatus for elevating oil and other fluids, and has for its object to provide improvements of this general nature, particularly pertaining 5 to the elevation of oil from deep wells, which will be generally superior from the stand-point of efficiency, economy and serviceability, taken in conjunction with inexpensiveness in cost, installation, utilization and 10 maintenance, and facility of control, and which will be generally superior for the purposes for the accomplishment of which the invention is adapted.

With the above and other objects in view, 15 the invention consists in the novel and useful provision, formation, association, combination, relative arrangement and conjoint use and grouping and sequence of parts, members, features, steps and acts, all as herein- 20 after described, shown in the drawings, and finally pointed out in claims.

In the drawings:

Figure 1 is a side elevation, partly broken away and partly in section and partly conventional, in illustration of the utilization of 25 my improved process of elevating fluids and of one form or organization of apparatus adapted for use to such ends, such apparatus being shown as introduced in part within a 30 well hole and casing therein;

Figure 2 is an enlarged fragmentary view 35 of a portion of the disclosure in Figure 1, of features which are introduced within the well hole;

Figure 3 is a further enlarged fragmentary 40 sectional view of valve means introduced within the tubing or piping shown in Figures 1 and 2;

Figure 4 is an enlarged detail fragmentary 45 sectional view, partly in elevation, and partly broken away, of further features shown in Figures 1 and 2 and adapted to be introduced within the well hole;

Figure 5 is a detail vertical sectional view 50 taken upon the line 5-5, Figure 4, looking in the direction of the appended arrows; and,

Figure 6 is a detail transverse sectional view taken upon the line 6-6, Figure 5, and looking in the direction of the appended 55 arrows.

Corresponding parts in all the figures are designated by the same reference characters.

Referring with particularity to the drawings, I have shown in Figure 1 at A a string of casing or tubing introduced within a well hole B which has been produced in earth formation C, there being disposed within such tubing or casing a string or plurality of lengths of pump tubing D through which liquid, such as oil, is to be elevated to the surface and conducted to a tank E or other repository or point of discharge. This tubing D is provided at spaced points or in spaced zones with standing valves E of standard or any preferred form, including, in the illustration shown in the drawings, in each instance, a ball check valve e within a cage 7, such cage having an uprising stem 8 terminating in an eye 9, which may be engaged by a grab device or fishing tool of any desired construction for the purpose of unseating and withdrawing the standing valve and lifting it to the surface prior to pulling the pump tubing from the well and uncoupling it section by section. In this manner any accumulated fluid in the pump tubing may be discharged therefrom prior to pulling the tubing. A convenient and satisfactory grab device or fishing tool for the purpose last stated constitutes the subject of another application 70 for Letters Patent for grab device or fishing tool filed by me simultaneously with the filing of this application and executed by me the same day.

In practicing my present invention, I provide a further string of tubing F, which may consist of separate joints or sections coupled together, and which depends within the well hole or tubing A therein alongside the string of tubing D, such tubing being preferably of smaller internal diameter and being coupled or joined to or with the tubing D by a coupling or union f, which comprises a main tubular or body portion 10 which is angled outwardly and downwardly into a lower terminal portion 10', which is coupled or joined to a strainer G or lower terminal portion of the tubing D by a coupling g, which may constitute a cage for a ball check valve 11 having a seat 12 in such coupling and serving to 95 100

check return flow of fluid to the strainer G. At one side of the lower portion 10^a of the coupling f is provided a transverse tubular portion 10^b, opening at one end laterally and upwardly for communication with the lower end of the tubing F which is interrupted just above such chamber 10^b to include a housing or coupling 13 for a check valve 14 provided with a seat 15, such check valve being disclosed as of the flap valve type and acting to prevent return or upward flow of fluid forced or passed downwardly through the tubing F from a pump H of any preferred or suitable type, mounted on a base h at the earth's surface adjacent to the mouth of the well hole and adapted to supply oil or other fluid, preferably heated, to the tubing F, such fluid being supplied through piping K from a tank or container L within which such fluid, such as oil, supplied thereto through a pipe 1 from the pump tubing D, may be suitably heated as by a steam coil 16 receiving steam through a branch pipe or leg 17 from a steam pipe 18 supplying steam to the pump H from a suitable steam plant M. Thus, a portion of the oil or other fluid recovered from the instant well may be diverted for use in accordance with the invention and, preheated if desired, introduced within the well hole and forced into the well tubing D through the coupling f. The other end of the chamber 10^b in the coupling f communicates with an upward extending nozzle 10^c which rises within and throughout its major portion is surrounded by the upper portion of the coupling f, where it extends vertically, at 10^d, and is joined to the pump tubing, as by an enlargement 10^e having threaded connection with the coupling f. Thus, the coupling f comprises a lower vertical or substantially vertical portion, an intermediate upwardly inclined portion, 10^a, and an upper terminal portion 10^d, within which the nozzle 10^c opens; such coupling likewise including the chamber 10^b whereby such nozzle communicates with the tubing F. The thread connection 10^e between tubing F and coupling f is preferably a left-hand thread, whereby the tubing F may be uncoupled and pulled before pulling the tubing D.

In the practice of the invention and utilization of apparatus embodying the same and of the process incident to such practice, whether by use of the specific apparatus disclosed and heretofore described or by other analogous or equivalent apparatus, as, for instance, for the elevation of oil from deep wells, let it be assumed that the oil in such well stands at the level indicated by the words "fluid level" in Figure 1. Thus, fluid will stand in the pump tubing D above the nozzle 10^c. Thereupon the tubing F is supplied with fluid as from the tank L through the agency of the pump H, and such fluid being so supplied by the pump under pressure,

a jet action will be produced at the top of the nozzle 10^c within the column of fluid standing in the coupling f. This jet action will disturb the balance or equilibrium between the column of fluid in the tubing D and the parallel column in the tubing F, and, by induction, produce an upward urge or movement of the fluid in the pump tubing D. Likewise, the agitation produced by such jet action will tend to disassociate or separate the gaseous content of the fluid, in the case of hydro-carbon oils, and such liberated gas bubbles will produce levitation upon the fluid standing in the pump tubing and tend to cause it to ascend. This agitation of the oil produces an effect similar to that resultant upon shaking of a siphon bottle filled with fluid charged with carbonic acid gas, or a soda water bottle similarly filled and charged, the energy of the liberated gaseous content producing an ebullition or boiling translated into ascending or discharge action of the liquid contents. Likewise, if the fluid forced downwardly through the tubing F be heated, the heat units thereof increase the gaseous liberation, and, causing a more or less sudden expansion of the fluid in the well tubing, tends to produce a partial vacuum, the effect of which will be to assist the upward movement of such column. Thus, the fluid in the tubing D receives an upward urge through gaseous levitation, by diminished air pressure in the tubing D due to partial vacuum created, and by the jet action or induction, resultant in mechanical lift consequent upon the introduction of the fluid from the tubing F into the tubing D through the nozzle 10^c. All of these acts promote and maintain, either taken together or separately applied, a discharge of the fluid from the well, such fluid being impounded from zone to zone within the pump tubing by the check valves E.

It is obvious that the invention may be utilized and applied in connection with the elevation of other fluids than hydrocarbon oils, and for other pumping purposes, both as to the various and several features of the apparatus and the process heretofore disclosed; also that many changes and variations may be made from such disclosure and from the showing of the drawings, in practicing such invention, without departing from the true spirit of the invention.

Having thus disclosed my invention, I claim and desire to secure by Letters Patent:

1. The method of elevating oil having a gasifiable constituent, from an oil well which consists in introducing into a body of such liquid in the lower end of an eduction tube oil heated to a temperature sufficient to gasify said constituent, the introduction of the second mentioned liquid being in such a way as to produce an entrainment of the first mentioned liquid.

2. The method of elevating oil having a

gasifiable constituent, from an oil well which consists in introducing into a body of such liquid in the lower end of an eduction tube oil heated to a temperature sufficient to gasify
5 said constituent, the introduction of the second mentioned liquid being in such a way as to produce an entrainment and agitation of the first mentioned liquid.

In testimony whereof, I have signed my
10 name to this specification.

JOSEPH H. SLOCUM.
